UNITED STATES PATENT OFFICE

2,435,425

MAGNETIC CONTROL DEVICE

Lewis C. Cunningham, Los Angeles, Calif., assignor to General Controls Co., Glendale, Calif., a corporation of California

Application April 13, 1943, Serial No. 482,880

6 Claims. (Cl. 175—336)

1

My present invention relates to magnetic control devices of the type which includes an armature movable to operate control means such as electrical contacts, pilot valves, or the like. More particularly, the invention relates to such devices wherein a permanent magnet is provided for normally holding the armature in attracted position, and having means movable into the field of the magnet for so shunting the flux thereof that the armature is released.

An object of this invention is to provide a control device, of the character described, wherein the magnet is of U-shape and the shunting means is movable to a position between the side arms of the magnet, or adjacent the polar ends thereof.

Another object is to provide a device, of the character described in the preceding object, wherein the armature is disposed in a plane substantially parallel to that of the arms of the magnet so that a compact structure is formed.

Another object is to provide the U-shaped magnet with means which extend from the polar ends of the magnet, in a direction at right-angles to the plane of the arms thereof, to form pole faces in a plane parallel to that of the arms.

Another object is to provide the control device with an additional U-shaped magnet which is arranged with its polar ends adjacent, and opposed to, the polar ends of the other magnet; thereby minimizing the leakage flux of the magnets, and permitting the shunting means to be symmetrically arranged between the polar ends of the magnets.

A still further object is to provide, in the application of the above-described control device to a fluid control valve, means connecting the shunting means to the closure member of the valve, and means interposed between the shunting means and the magnet for shielding the control device from the fluid controlled by the valve.

Other objects and advantages of the invention will be found in the description, the drawing, and the claims; and, for full understanding of the invention, reference may be had to the following detailed description and accompanying drawing, wherein:

Figure 1 is a longitudinal sectional view of a fluid control valve which includes, at its upper end, a magnetic control device embodying my invention;

Figure 2 is a transverse section taken along the line 2—2 of Fig. 1;

Figure 3 is a fragmentary longitudinal section taken along the line 3—3 of Fig. 2;

Figure 4 is a view, in perspective, of the magnetic control device shown in Figs. 1—3; and

Figures 5, 6 and 7 are diagrammatic views of typical control systems which include the magnetic device.

Referring first to Figs. 1—4 of the drawing, the

2

numerical 11 indicates a valve casing having a ported partition 12 providing a valve seat 13 with which a closure member 14 cooperates. Mounted on the apertured top wall of the casing is an electromagnetic operator comprising a hollow cylindrical core 15, an annular coil winding 16, and a reciprocable plunger 17 which is connected by a stem 18 to the closure member 14. On the top of the core 15 is a disk-shaped base 19, of insulating material, which supports the magnetic control device of the invention. The base is mounted on the core by means of a pair of screws 20, extending from the core, which pass freely through holes in the base and are provided at their ends above the base with nuts 21. Around the portion of each of the screws 20 below the base 19 is a compression spring 22 which urges the base into engagement with the nuts 21. By turning these nuts, the base can be adjustably moved along the axis of the electromagnet. Enclosing the space above the electromagnet is a cap 23, through the top wall of which there extend the leads 24 of the electromagnet coil winding 16 which pass through openings in the core 15 and base 19.

On the base 19 is a pair of U-shaped permanent magnets 25—26 which are arranged in a single horizontal plane with the free ends of their respective side arms in adjacent relation. The magnets are secured to the base by a pair of rectangular posts 27—28 (Fig. 4) which are interposed between the adjacent ends of the side arms of the magnets in abutting relation thereto and are provided with enlarged head portions 29—30 for engagement with the top surfaces of the magnets; the posts being secured to the base by screws 31 (Fig. 3). The magnets 25—26 are arranged in opposing relation, i. e., the adjacent ends of the side arms of the magnets have the same polarity, as is indicated by the letters N and S in Fig. 4. The posts 27—28 are of magnetic material, such as soft iron, and their top surfaces thus form a pair of pole faces, marked N and S, which are effectively the common poles of the two magnets. Cooperable with the magnets, and positioned immediately above and substantially parallel to the pole faces of posts 27—28, is an armature 32 (Fig. 3) which is attached at its bent-up left-hand end to an apertured flexible metal strip or hinge 33 which is supported by an angle bracket 34 secured to the base 19 by screws 35. The armature 32 carries a switch arm 36 which cooperates with contact screws 37—38 threaded respectively in brackets 39—40 secured to the base 19. The switch constituted by arm 36 and contacts 37—38 is adapted to be connected in circuit with apparatus, to be controlled in accordance with the switch arm position, by connecting the leads of the apparatus to the brackets 34, 39 and 40—no such connections being shown in Figs. 1—4. The

armature is normally held by the magnets in attracted position with respect to the pole faces of posts 27-28 (so that the switch arm is in engagement with the lower contact screw 37) and is biased in a direction away from the pole faces by the force of a tension spring 41 which is tightly threaded at its lower end on screw 35 (Fig. 3) and is freely threaded at its other end on a screw 42 which is a clearance fit in an opening through an extension 43 of the armature. By turning screw 42, the tension of spring 41 can be adjusted.

Connected to the upper end of the electromagnet plunger 17 is a rod 44 having at its top an enlarged portion or head 45, of soft iron, which is a sliding fit within the reduced tubular upper portion 46 of a non-magnetic cup or liner 47 having at its mouth a flange 48 which is interposed at its margin between the valve casing 11 and the core 15. The liner 47 serves to shield the electromagnet and the magnetic switching device from the fluid controlled by the valve, as well as to magnetically separate the upper portion of the plunger 17 from the core 15 when the plunger is raised by energization of coil 16. The reduced upper portion 46 of the liner extends through central openings in the core 15 and base 19 and is of such length that its closed top end is approximately flush with the pole faces of the posts 27-28; the outer side surface of the portion 46 being in engagement with the inner corners 49 (Fig. 4) of the side arms of the magnets which are ground to conform thereto.

When plunger 17 is raised by energization of its electromagnet, the soft-iron head 45 of rod 44 is interposed between the polar ends of the magnets 25-26 so that the flux thereof is shunted by the head, the resultant reduction of magnetic attraction of the armature permitting the force of its bias spring 41 to move it in a direction away from the magnets so that the switch arm 36 engages the upper contact screw 38. When, upon deenergization of the electromagnet, the head 45 is retracted, the armature returns to its attracted position as shown. In the structure of Figs. 1-4, the controlling function of the magnetic switching device does not appear, since the structure is intended merely to illustrate the arrangement of the device with respect to typical means for operating the shunting head 45. However, it is apparent that the switching device could be employed to control an electrical circuit including means, such as signal lights, for remotely indicating the condition of the closure member of the valve. In some applications of the switching device, it is important that the armature be released or attracted when the shunt operating means reaches a particular point in its travel; for that reason, the base 19 is arranged so that it can be raised or lowered (as has been described) to determine that point, it being understood that under normal bias of the armature the same is released when the shunting head 45 is inserted only partially between the magnets.

Referring now to the diagram of Fig. 5, the magnetic switching device, described in connection with Figs. 1-4, is shown in simplified form. It comprises a switch blade 60 which is biased by its own resilience in an upward direction. Attached to the underside of the switch blade is an armature 61 which cooperates with a single U-shaped permanent magnet 62, the polar ends of which are marked N and S. Carried by a solenoid plunger 63, having an energizing coil winding 64, is a soft-iron rod 65 which is ar-

ranged to project between the side arms of the magnet 62, when plunger 63 is in its raised position as shown, to shunt the flux of the magnet so that the armature assumes its unattracted position wherein the switch blade 60 is in engagement with a contact element 66. Extending from the bottom of plunger 63 is a stem 67 which, by way of example, is shown provided with a closure member 68 cooperable with a valve seat 69. The lower portion of stem 67 is reduced in diameter to provide a shoulder 70 with which an electromagnetic latching plunger 71 cooperates. This plunger is biased toward the valve stem by a compression spring 72 and is retractable therefrom upon energization of its coil winding 73. The coil windings 64 and 73 are connected at one of their ends to contacts 74 and 75, respectively, which are engageable by a manually-operable switching member 76. The other end of the main plunger winding 64 is connected to a contact element 77 which is engageable by the switch blade 60 when the armature 61 is in its attracted position with respect to magnet 62; the other end of the latching plunger winding 73 being connected to the upper contact element 66. The switching member 76 is connected, in series with a source of electrical energy 78, to ground; switch blade 60 also being grounded. Thus, when the switching member 76 is moved into engagement with contact 75, current then flows through the latching plunger winding 73 (contact element 66 being engaged by switch blade 60), thereby effecting retraction of the latching plunger so that the main plunger 63 falls by gravity. In the downward movement of the main plunger, the soft-iron rod 65 is removed from the field of magnet 62 so that armature 61 is downwardly attracted, thereby effecting disengagement of switch blade 60 from contact 66 so that the energizing circuit of the latching plunger 71 is broken and that plunger moves into engagement with the unreduced upper portion of stem 67. If the switching member is now moved back into engagement with contact 74, current flows through the winding 64 of the main plunger (switch blade 60 now being in engagement with contact element 77) and that plunger moves upwardly; the plunger 71 being forced by its bias into latching position below shoulder 70 when the main plunger is near the end of its stroke. Slight continued upward movement of the main plunger effects magnetic release of the armature, by shunting of the magnet flux by rod 65, so that the resultant separation of the switch blade from contact 77 breaks the main plunger circuit; the parts assuming the positions shown in Fig. 5.

In Fig. 6, the main parts are identical with those of Fig. 5 and have therefore been assigned the same reference numerals and need not further be described. The chief difference lies in the provision of a momentary-contact manually-operable switching member 79 for controlling the energizing circuits of the main and latching plunger coil windings 64 and 73, so that it is not necessary to automatically break these circuits (as in Fig. 5) upon completion of the plunger stroke—the right-hand ends of the windings 64 and 73 leading directly to ground, as indicated. The magnetically operated switch 60, 66, 77 is here employed to control the energization of circuits (entirely independent from the plunger circuits) which include signal lights 80 and 81 and an additional source of electrical energy 82. The manual switching member 79

is biased by its own resilience to a neutral position out of engagement with contacts 74 and 75. The parts are shown in the figure in the positions assumed after the member 79 had momentarily been brought into engagement with contact 74 so that the main plunger 63 was raised to its latched position, thereby effecting magnetic release of armature 61 due to the shunting of magnet 62 by rod 65—the condition of the main plunger being indicated by the resultant 10 energization of the circuit of signal light 80. If the lower contact 75 is now engaged by member 79, the latching plunger 71 is retracted and the main plunger falls—the resultant downward attraction of armature 61 effecting deenergization 15 of signal light 80 and energization of the other light 81.

In the arrangement of Fig. 7, the magnetic switching device is employed to control the lifting-coil circuit of a solenoid plunger 83 having a lifting coil 84 and a holding coil 85. These coils are connected together at one of their ends and to a contact 86 which is engageable by a manually-operable switching member 87 which is adapted to connect the source 78 to the coils in common. The other end of the lifting coil 84 is connectable to ground, through the contact 77 of the magnetic switching device, to complete its energizing circuit; the other end of holding coil 85 being directly grounded. In the figure, 20 the plunger 83 is shown held in its raised position due to energization of coil 85 (switching member 87 being closed); and the blade 60 of the magnetic switching device is in its released position, in engagement with a stop 88, due to the shunting of magnet 62 by rod 65. If the switching member 87 is opened, the holding coil 85 is deenergized and the plunger 83 falls; the magnetic switching device assuming its attracted position with blade 60 in engagement with contact 77. If 25 the member 87 is then reclosed, both lifting and holding coils are simultaneously energized and the plunger is raised, the circuit of the lifting coil 84 being automatically opened when the plunger approaches the end of its stroke, due to 30 the release of blade 60 from contact 77; the continued energization of coil 85 then sufficing to hold the plunger in its raised position.

While I have herein shown and described a specific embodiment of my invention, I wish it to be understood that modifications may be made without departing from the spirit of the invention, and that I intend therefore to be limited only by the scope of the appended claims.

I claim as my invention:

1. In a magnetic control device: a U-shaped permanent magnet, flux-conducting means extending from each of the polar ends of the arms of said magnet in a direction at right-angles to the plane of the arms of the magnet to form a pair of pole faces in a plane parallel to that of said arms, a generally flat armature cooperable with the magnet and disposed in a plane substantially parallel to that of said pole faces, said armature normally being held by the magnet in 40 attracted position with respect to said pole faces and biased in a direction away from them, and means movable into a position between the side arms of the magnet for so shunting the flux thereof that the armature then moves under the 45 force of said bias.

2. In a magnetic control device: a U-shaped permanent magnet, a generally flat armature cooperable with said magnet and disposed in a plane substantially parallel to that of the arms 50

of the magnet and adjacent one side of said arms, said armature normally being held by the magnet in attracted position with respect thereto and biased in a direction away from it, and means insertable between the arms of the magnet from the side thereof away from the armature and movable in a direction at right-angles to the plane of said arms, said means when in inserted position being effective to so shunt the flux of the magnet that the armature then moves under the force of said bias.

3. In a magnetic control device: a U-shaped permanent magnet, flux-conducting means extending from each of the polar ends of the arms of said magnet in a direction at right-angles to the plane of the arms of the magnet to form a pair of pole faces in a plane parallel to that of said arms, a generally flat armature cooperable with the magnet and disposed in a plane substantially parallel to that of said pole faces, said armature normally being held by the magnet in attracted position with respect to said pole faces and biased in a direction away from them, and means insertable between the arms of the magnet from the side thereof away from the armature and movable in a direction at right-angles to the plane of said arms, said means when in inserted position being effective to so shunt the flux of the magnet that the armature then moves under the force of said bias.

4. In a magnetic control device: a pair of U-shaped permanent magnets arranged in a single plane with the poles thereof in adjacent and magnetically-opposed relation, a generally flat armature cooperable with said magnets and disposed in a plane substantially parallel to that of the arms of the magnets and adjacent one side of said arms, said armature normally being held by the magnets in attracted position with respect thereto and biased in a direction away from them, and means insertable between the arms of the magnets from the side thereof away from the armature and movable in a direction at right-angles to the plane of said arms, said means when in inserted position being effective to so shunt the flux of the magnets that the armature then moves under the force of said bias.

5. In a magnetic control device: a pair of U-shaped permanent magnets arranged in a single plane with the poles thereof in adjacent and magnetically-opposed relation, flux-conducting means interposed between each of the adjacent pairs of poles of said magnets and extending at right-angles to the plane of the arms of the magnets to form a pair of pole faces in a plane parallel to that of said arms, a generally flat armature cooperable with the magnets and disposed in a plane substantially parallel to that of said pole faces, said armature normally being held by the magnets in attracted position with respect to said pole faces and biased in a direction away from them, and means insertable between the arms of the magnets from the side thereof away from the armature and movable in a direction at right-angles to the plane of said arms, said means when in inserted position being effective to so shunt the flux of the magnets that the armature then moves under the force of said bias.

6. In a magnetic control device: a pair of U-shaped permanent magnets arranged in a single plane with the poles thereof in adjacent and magnetically-opposed relation; flux-conducting means interposed between each of the adjacent pairs of poles of said magnets and extending at

right-angles to the plane of the arms of the magnets to form a pair of pole faces in a plane parallel to that of said arms, a flat elongated armature cooperable with the magnets and disposed in a plane substantially parallel to that of said pole faces, said armature being pivoted at one end and lying transversely of the common axis of the magnets, said armature normally being held by the magnets in attracted position with respect to said pole faces and biased in a direction away from them, and means insertable between the arms of the magnets from the side thereof away from the armature and movable in a direction at right-angles to the plane of said arms, said means when inserted position being effective to so shunt the flux of the magnets that the armature then moves under the force of said bias.
